HERMAN C. HIRSCHY, OF DULUTH, AND RALPH C. HITCHCOCK, OF MINNEAPOLIS, MINNESOTA, ASSIGNORS TO THE HIRSCHY COMPANY, OF DULUTH, MINNESOTA, A CORPORATION OF MINNESOTA.

WRINGER-CONTROL MECHANISM.

Application filed April 17, 1925. Serial No. 23,905.

This invention relates to an improved control mechanism for power-driven wringers and more particularly to such a device which functions to lock the wringer in its adjusted positions and also to shift the operating mechanism to operatively connect the wringer rolls with or disconnect them from a driven member or shaft.

Clothes wringers such as are commonly used in connection with power washing machines are usually pivotally mounted upon a post or standard supported by the frame of the washing machine. The mounting of the wringer upon its supporting means is usually such that the wringer may be adjusted or swung to a plurality of positions about a given center, this center usually being the axis of the wringer drive shaft. The purpose of thus adjustably mounting the wringer upon the frame of the washing machine is to provide means whereby the wringer may be shifted or swung from a position over the machine tub to a position over a laundry tub or other device, without the necessity of having to move or shift the position of the washing machine upon the floor. Such clothes wringers are therefore usually provided with two control levers, one for locking the wringer in its adjusted positions and the other for shifting the clutch mechanism to start and stop the wringer rolls.

The necessity of having two such control levers to control the operation of a power clothes wringer has been found objectionable and sometimes dangerous in that there is always a possibility of the wringer-locking bolt or latch becoming unlocked while the wringer is operating under load, thereby allowing the wringer to be forcibly swung around its pivotal point caused by the action of the drive gears thereof. It is therefore desirable that means be provided whereby the wringer drive mechanism cannot possibly be actuated to drive the wringer rolls while the wringer locking bolt or latch is in unlocked position.

The novel wringer control mechanism featured in this invention is so constructed that the wringer rolls cannot possibly be started while the locking bolt is in unlocking posi-

tion. Its construction is such that the locking bolt must positively be moved into locking position before the clutch mechanism can be actuated sufficiently to cause the wringer rolls to be rotated. This novel control mechanism is also provided with means whereby the wringer rolls after having been started must be brought to a stop before the locking bolt can be moved from locking into unlocking position to permit the swinging of the wringer from one position to another. The starting and stopping of the wringer rolls, and also the locking of the wringer in its adjusted positions, is accomplished by a single control lever, thereby providing a control mechanism which may be conveniently operated and actuated by the use of one hand thereby allowing the operator the use of the other hand for guiding the clothes through the wringer rolls or other purposes.

The particular object of the invention therefore is to provide a wringer control mechanism of simple and inexpensive construction which will be foolproof and positive in action and which may be controlled by a single control lever.

Other objects of the invention will appear from the following description and the accompanying drawings and will be pointed out in the annexed claims.

In the drawings, there has been disclosed a structure designed to carry out the various objects of the invention, but it is to be understood that the invention is not confined to the exact features shown as various changes may be made within the scope of the claims which follow.

In the accompanying drawings forming part of this specification,

Figure 1 is a vertical sectional view on the line 1—1 of Figure 3 showing the general construction of the operating mechanism, same being shown in inoperative or neutral position;

Figure 2 is a bottom view of the control head;

Figure 3 is a horizontal sectional view on the line 3—3 of Figure 1;

Figure 4 is a cross sectional view on the lines 4—4 of Figures 1 and 2 showing the locking bolt in unlocked position;

Figures 5, 6 and 7 are similar detail views showing the parts in different positions;

Figure 8 is a plan view of the upper portion of the wringer supporting post or member showing the apertures provided therein for receiving the locking bolt to lock the wringer in its adjusted positions.

In the selected embodiment of the invention here shown, for purposes of disclosure, there is illustrated a common form of wringer comprising the usual rolls 11 and 12 mounted in a frame 13 secured to the wringer control head. The rolls 11 and 12 are driven from a shaft 14 through the usual pinions 15 and 16 as shown in Figure 1. In wringers of this type, the upper roll 11 is usually provided with suitable tension means for exerting a downward pressure thereagainst, but as the wringer forms no part of the present invention, such means are not shown in the drawings.

The novel control mechanism featured in this invention preferably consists of an integral casting or head 17 which is shaped to form a housing to receive the operating mechanism. A reduced portion or neck 18 is preferably provided on the lower wall of the housing 17 and has a circular flange 19 provided on the lower end thereof adapted to be seated upon an annular flange 21 provided upon or secured to the upright post 22 of the washing machine frame. The post 22 is preferably hollow and has a drive shaft 23 rotatably mounted therein which is driven from a suitable drive mechanism mounted upon the washing machine, and which mechanism is not shown in the drawings. The post 22 is provided with an upwardly extending cylindrical end-portion 24 which is adapted to be received in a bore 25 provided in the neck 18 of the housing, thereby to provide a pivotal connection between the wringer and washing machine frame.

A socket 26, preferably square in cross section, is terminally provided in the drive shaft 23 and is adapted to receive the squared end-portion 27 of an upright clutch shaft 28 mounted in bearings 29 and 30 provided in the lower and upper walls of the housing 17. By thus operatively connecting the clutch shaft 28 with the drive shaft 23 by means of the squared end-portion 27 and socket 26, it will be noted that the entire wringer and its operating mechanism including the housing 17, may readily and conveniently be detached from the washing machine by simply upwardly lifting the wringer and the housing. In like manner, the wringer and its operating mechanism may conveniently be mounted upon the post 22 of the washing machine frame by simply inserting the cylindrical extension 24 into the socket 25 and also the squared end-portion 27 of the clutch shaft 28 into the socket

26 in the drive shaft. As shown in Figure 1, downward thrust of the clutch shaft 28 is preferably taken up by a suitable thrust washer 20 and a split lock ring 40 demountably seated in an annular groove provided in the shaft adjacent the upper end thereof.

A beveled pinion 31 is rotatably mounted upon the clutch shaft 28 adjacent the bearing 29 and a similar pinion 32 is also mounted upon the clutch shaft 28 adjacent the upper bearing 30. The upper portion of the clutch shaft is preferably turned down, as shown in Figure 1, to provide a shoulder 33 which functions to retain the pinion 32 in its proper position with relation to the beveled gear 34 with which the two pinions intermesh. A gear 34 is suitably secured to the driven shaft 14 which is mounted in a bearing 35 provided in one of the walls of the housing 17. Thus, it will be seen that when either of the pinions 31 or 32 is driven, power will be transmitted to the shaft 14 and therefore to the wringer rolls through the pinions 15 and 16. A grooved clutch member 36, of ordinary construction, is slidably mounted upon the clutch shaft 28 between the beveled pinions 31 and 32, and is prevented from relative rotation thereon by means of the flattened surfaces 37 provided on opposite sides of the clutch shaft, as particularly shown in Figure 3. Clutch teeth or jaws 38 and 39 are provided on the pinions 31 and 32, respectively, so that when the clutch member 36 is moved into operative connection with the jaws of either one of the pinions, power will be transmitted from the clutch shaft 28 through the jaws of the clutch to one of the pinions, and thence through the gear 34 to the shaft 14.

The means provided for actuating the clutch member 36 preferably resides in the provision of a block 41 which is pivotally mounted upon a crank pin 42 carried by a crank 43 which is secured to a control shaft 44 as shown in Figures 1 and 3. The control shaft 44 is mounted in a bearing 45 provided in the wall of the housing and has a control lever 46 terminally secured thereto by means of a nut 47. A hand grip 48 is provided on the lever 46 for the convenience of the operator in shifting the lever from one position to another. By means of the above-described mechanism, it will readily be noted that when the lever 46 is shifted from its vertical position as shown in Figure 1 to the full line position shown in Figure 7, that the clutch operating block 41 will be moved from the position shown in Figure 1 to that shown in Figure 7, thereby shifting the clutch member 36 into driving connection with the jaws 39 on the upper pinion 32. Such operation of the control lever will cause the driven shaft 14 to be driven in one direction, while if the clutch member 36 is shifted into driving connection

with the jaws 38 on the lower pinion 31, the driven shaft 14 will be rotated in the opposite direction, thereby providing means for controlling the direction of rotation of the 5 two wringer rolls 11 and 12.

An important feature of this invention resides in the novel means provided for positively preventing the wringer rolls from being operatively connected to the drive 10 shaft 23 until after the wringer has been locked in one of its adjusted positions. The means provided for obtaining the above desired control is accomplished by operatively connecting to the control lever 46, 15 the means provided for locking the wringer in its adjusted positions so that the latter must be actuated before the clutch member 36 is moved into driving connection with one of the pinions 31 or 32. The means provided for locking the wringer in its adjusted 20 positions consists of a locking bolt 49 mounted in a socket 51 provided in the reduced portion or neck 18 of the housing. The lower end of the locking bolt is preferably 25 slightly tapered, as shown in the drawings, so that it may readily enter one of the apertures 52 provided in the annular flange 21 of the supporting post or standard 22 (see Fig. 8). The major portion of the 30 locking bolt 49 is preferably reduced in diameter as shown so as to provide a shoulder 53. A compression spring 54 is mounted in the socket 51 and is coiled about the locking bolt so as to have its lower end bearing 35 against the shoulder 53 and its upper end seated in the bottom of the socket, thereby tending to downwardly force the locking bolt against the flange 21 or into one of the apertures 52.

The means provided for actuating the locking bolt 49 consists preferably of an L-shaped member 55 having its lower horizontal portion apertured to receive the upper end of the locking bolt as shown in Figures 40 1, 4, 5, and 6. A pin 56 is mounted in the upper end of the locking bolt so that when the L-shaped member 55 is upwardly moved, the locking bolt will be moved therewith. An elongated opening 57 is provided in the 45 L-shaped member 55 to receive the control shaft 44 as clearly shown in Figure 1. An anti-friction roller 58 is mounted upon a stud 59 secured to the upper end of the member 55. This roller is adapted to ride 50 upon the surface of a cam member 61 mounted upon the control shaft 44 and preferably integrally formed with the crank arm 43 (see Figures 1 and 3). The cam member 61 is provided with a high or neutral 55 point 62 which, when the control lever is in neutral position as shown in Figures 1 and 4, will cause the roller 58, and therefore the L-shaped member 55 to be raised to the position shown with the result that the lower 60 end of the locking bolt 49 will be moved out

of engagement with the annular flange 21 of the post 22. When thus positioned, the clutch member 36 will be in neutral position and the wringer will be inoperative, also when thus positioned, the wringer may be 65 swung from one position to another about the axis of the drive shaft 23 as a center. Before the wringer rolls can be started, the control lever 46 must be moved from the vertical position shown in Figures 1 and 4 70 to the horizontal full line position shown in Figures 6 and 7. Such movement of the control lever, however, cannot be completed unless the locking bolt 49 is in alignment 75 with one of the apertures 52 in the flange 21 so that the bolt may be inserted into one of the apertures as shown in Figures 6 and 7. The means provided for thus preventing the complete movement of the control lever should the locking bolt be out of alignment 80 with one of the apertures 52, as shown in Figures 4 and 5, consists in the provision of a pair of stop lugs 63 provided on the lower portion of the cam member 61. These lugs 85 are adapted to engage the upper end of the locking bolt 49 when the latter is in the position shown in Figures 4 and 5. In moving the control lever from the neutral position, shown in Figures 1 and 4 to the full line 90 position shown in Figure 5, the clutch member 36 will be moved from the full line position to one of the dotted line positions 95 shown in Figure 1, wherein it will be noted that it will still be out of contact with the teeth of both of the beveled pinions 31 and 32. Further movement however, will be prevented as a result of one of the lugs 63 engaging or contacting with the upper end 100 of the locking bolt. After the lever has been moved to the position shown in Figure 105 5, the operator may swing the wringer about the shaft 23 until the lower end of the locking bolt is brought into alignment with one of the apertures 22 after which the spring 54 will automatically cause the locking bolt to 110 be lowered into such aperture with the result that the movement of the lever may be completed to actuate the clutch mechanism to start the wringer rolls. Figures 6 and 115 7 show the clutch lever and parts in operative position. By referring particularly to Figure 6, it will be noted that the stop lugs 63 on the cam member 61 also function as a means for limiting the movement of the control lever.

When it is desired to stop the wringer rolls, the control lever will first be moved from the position shown in full lines, Figures 6 and 7, to the full line position shown in Figure 5. Such movement of the control lever will be sufficient to move the clutch member 36 out of driving connection with one of the pinions 31 and 32, but which movement, however, will be insufficient to cause the locking bolt to be moved out of 120 125 130

engagement with its complementary aperture 52 in the flange 21. The final upward movement of the lever from the full line position shown in Figure 5, to that shown in Figures 1 and 4 will cause the locking bolt to be upwardly moved to the position shown in Figures 1 and 4, after which the wringer may be swung to any one of its adjusted positions.

- 10 From the foregoing, therefore, it will readily be seen and understood that by the employment of this novel control mechanism in conjunction with a power driven wringer and washing machine, it will be 15 impossible for the wringer rolls to be started before the wringer has been locked in one of its adjusted positions. Also, after the wringer rolls have been started, the clutch mechanism must be moved to release position 20 to stop the rotation of the wringer rolls before the locking bolt is moved sufficiently to cause the wringer to be unlocked to permit its adjustment from one position to another.
- 25 The housing 17 is preferably open on opposite sides, as shown in Figure 3, in order to gain access to the interior thereof. These openings may be conveniently closed by means of suitable closures 64. Various 30 changes and modifications may be made in the various details of the construction herein shown without departing from the scope of the invention.

We claim as our invention:

- 35 1. A wringer adapted for adjustment to different working positions and having a roll-driving mechanism including a control-clutch, a locking member for holding said wringer in adjusted positions, a rock-shaft 40 for operating the clutch and having a cam thereon, means for normally holding said locking member in its locking position, means connected with the locking member and adapted to be actuated by the movement 45 of the cam for moving said locking member to unlocking position when said shaft is rotated to disengage the clutch, said connecting means being further adapted for entrainment by the locking member toward the 50 cam as said locking member travels to locking position, and said connecting member being engageable with the cam to limit shaft rotation.
- 55 2. A wringer adapted for adjustment to different working positions and having a roll-driving mechanism including a control clutch, a spring-actuated locking bolt for holding said wringer in its adjusted position, a rock-shaft and lever therefor, a cam 60 on the shaft, a link connected with said locking bolt and actuated by the movement of said cam in one direction to move said bolt to its releasing position, and into the path of said cam, said bolt spring returning said 65 bolt to its locking position, said shaft and

lever being adapted to return said clutch to its engaging position, when said bolt is moved out of the path of said cam.

3. A wringer comprising a pair of rolls and a driving means therefor, a rock-shaft, 70 a control lever thereon, a cam mounted on said rock-shaft, a locking member for locking said wringer in its adjusted positions, means connected to said locking member and guided by said shaft, and actuated by said 75 cam to move said locking member to its unlocking position, and means normally tending to move said locking member to its locking position.

4. A wringer adapted for adjustment to 80 different working positions and having a roll driving mechanism including a control clutch, a locking member for holding said wringer in its adjusted positions, a rock-shaft having means thereon for actuating 85 said control clutch, a cam also mounted on the rock-shaft, a movable member cooperative with the cam and having one end movably connected to the locking member, said movable member encircling and being slid- 90 able upon the shaft, and means functioning to automatically move said locking member into locking position.

5. A wringer mounted for adjustment in different working positions, a roll driving 95 mechanism, a rock-shaft operatively connected with said mechanism for shifting it to its working and non-working positions, said shaft having a cam, said cam having lugs thereon, a lock device for holding the 100 wringer in its working positions, means actuated by the movement of the cam for completely unlocking said lock device following the movement of said driving mechanism substantially to its non-working position, said 105 lock device in its unlocked positions being in the path of one of the said cam lugs and preventing the adjustment of said driving mechanism to its working position until said lock device is returned to its locking position.

6. A wringer mounted for adjustment in different working positions, a driving mechanism for the wringer including a clutch, a locking member for positively holding said 115 wringer in any one of its adjusted positions, control means for said driving mechanism including a rock-shaft and a cam secured to said shaft, and link means slidable upon said shaft and cooperating with said cam and locking member for moving said locking member when the control means is operated for throwing said clutch out of its working position.

7. A wringer adapted for adjustment to 125 different working positions and having a roll-driving mechanism including a control clutch, a locking member for holding said wringer in its adjusted positions, a rock-shaft and cam thereon, means for normally 130

holding said locking member in its locking position, and link means connected with said locking member and actuatable by the movement of said cam for moving said locking member to its unlocking position after said control clutch is disengaged, said cam-operated means adapted to be moved to release the locking member for automatic locking engagement during adjustment of the wringer.

8. A wringer adjustably mounted, a transmission mechanism for the wringer including a clutch, means for locking the wringer in adjusted position, a rock-shaft for controlling the clutch, a cam carried by said shaft, and slidably link means actuatable by said cam and slidably connected with said locking means for operating the same, said cam being contoured to only permit disengagement of said locking means after clutch withdrawal and to release the locking means to permit automatic locking action during adjustment of the wringer after clutch disengagement, said cam having lugs engageable with said locking means as a stop for preventing clutch engagement before automatic release of said locking member to locking position.

9. In a device of the class described, a base, a casing rotatable upon the base, a motion-reversing transmission mechanism carried by the casing including a shiftable clutch element, a latch bolt slidable in the casing and adapted for socketed locking engagement with the base by spring pressure, means including a rotatable shaft for operating the clutch, a link slidably connected with said bolt and shaft adapted to raise said bolt and to release the same to permit independent movement thereof to locking position, and a cam fixed to the shaft and adapted to translate the link.

10. In a device of the class described, a base, a housing rotatable thereon, transmission mechanism including a clutch, and a rotatable clutch operating means having a cam fixed thereto, a latch bolt engageable to hold the housing against rotation on the base, a link associated with said cam and bolt and operable by said cam, said cam being contoured to control the link to permit the bolt to automatically latch after the clutch is in, and to unlatch the bolt only after the clutch is disengaged.

11. A device of the class described comprising a journal post, a first drive shaft rotatable in said post and having an axially disposed socket in its upper end, said post having a flange with vertical openings therein, a casing rotatable about said post and against said flange, a lock bolt slidable in the casing and forcibly urged toward said flange, a reversing transmission mechanism in said casing including a vertical drive shaft removably but rotatably connected

with the socket of the first mentioned shaft, a transmission clutch slidable upon said second shaft, a rotatable clutch control shaft operatively connected with the clutch and having a cam fixed thereon, a link slidably connected with said control shaft and lock bolt, engageable by the cam and with the lock bolt to completely raise the bolt to non-locking position above the surface of the flange after the clutch reaches a neutral position, said cam being configurated to allow the link to fall when the lower end of the bolt is engaging the upper surface of the flange, thus conditioning the bolt for automatic unrestricted locking engagement with one of the openings of the flange as the casing is rotated, the cam being also configurated so as to be engaged by the upper end of said bolt to prevent a clutching-in operation while the bolt is thus conditioned.

12. A device of the class described comprising a base having openings therein, a housing rotatable upon the base, a lock bolt slidable in the housing and spring pressed toward the base and openings, a transmission mechanism carried by the housing including a clutch and locking bolt and clutch control shaft, said shaft having a cam fixed thereon, a link guided upon the shaft and bolt and engageable by said cam and with said bolt for completely withdrawing the bolt when the control shaft is operated to bring the clutch to disengaged position, said cam configurated for engaging the link to releasably hold the shaft in disengaged position and being additionally configurated to permit independent gravity movement of the link or positive movement thereof by the bolt to permit the bolt to slide upon the base conditioned for automatic locking engagement with an opening as the casing is rotated, and to forcibly engage the link against the cam and releasably hold the clutch in transmission position after locking engagement of the bolt, said cam having stops thereon respectively engageable with the bolt for preventing clutch engagement when the bolt is completely disengaged or conditioned for automatic engagement with the openings in the base.

13. A device of the class described including a base having openings therein concentric and parallel with an axis which is perpendicular to the base, a housing rotatable upon the base, a lock bolt slidable in said housing and parallel with the axis and spring pressed towards the base for engagement with an opening, a reversing transmission mechanism carried by the housing including a shiftable clutch, and a rotatable clutch-control shaft, hand-operable from a point exteriorly of the casing to control the clutch, the shaft axis being intersected by the axis of reciprocation of the

bolt, and said shaft having a cam fixed further configurated to permit gravity thereon in the plane of the bolt axis, a link slidably guided by said shaft and bolt and engageable by said cam, and with and by 5 said bolt for withdrawing the bolt from an opening and clear of the base when the control shaft is operated to disengage the clutch, said cam being configurated for engagement with said link to releasably hold 10 the clutch in such disengaged position and

base. independent lowering of the bolt for sliding engagement with the base to condition the bolt for locking engagement with said 15 base.

In witness whereof, we have hereunto set our hands this 13th day of April, 1925.

HERMAN C. HIRSCHY.
RALPH C. HITCHCOCK.
